(57) **CLAIM**

The ornamental design for the feather shaped pen holder with letter opener tip, as shown and described.

DESCRIPTION

FIG. 1 is a perspective view of a feather-shaped pen holder with letter opener tip in accordance with the invention;

FIG. 2 is a second perspective view thereof;

FIG. 3 is a third perspective view thereof;

FIG. 4 is a side elevational view thereof, the opposite side being a mirror image thereof;

FIG. 5 is a front elevational view thereof; and,

FIG. 6 is a rear elevational view thereof.

The writing instrument tips depicted by means of broken lines in FIGS. 1 and 2 have been shown for illustrative purposes only and form no part of the claimed design.
